DESIGN FOR A DRESS ENSEMBLE

Margaret Michelson, New York, N. Y.

Application April 29, 1937, Serial No. 69,031

Term of patent 3½ years

To all whom it may concern:

Be it known that I, Margaret Michelson, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a fragmentary view of the rear portion of the dress unit shown in Figure 2.

The rear portion of the skirt has a three gored arrangement, as indicated in Fig. 3.

The rear portion of the jacket unit is ornamented like the front.

The characteristic feature of my design resides in the jacket member of the ensemble, which jacket consists of overlapping folds, as shown and described.

I claim:

The ornamental design for a dress ensemble, substantially as shown, and described.

MARGARET MICHELSON.
